(57) **CLAIM**

What is claimed is the ornamental design for an accessory loop, as shown and described.

DESCRIPTION

FIG. 1 is a perspective view of an accessory loop showing a new design;

FIG. 2 is a top view of the accessory loop of FIG. 1;

FIG. 3 is a side view of the accessory loop of FIG. 1;

FIG. 4 is a front view of the accessory loop of FIG. 1;

FIG. 5 is a side view of the accessory loop of FIG. 1;

FIG. 6 is a bottom view of the accessory loop of FIG. 1; and,

FIG. 7 is a cross-sectional view taken along lines 7-7 as indicated in FIG. 4.

The broken lines shown in FIG. 4 represent the plane upon which the cross-sectional is taken and form no part of the claimed design.
